ANTIMAGNETIC WAR-MINE SUITABLE FOR
RAPID SETTING AND SOWING
Guido Romano, Pura, Tessin, Switzerland, assignor to
Anstalt Brind, Triesen, Liechtenstein, a corporation of
Liechtenstein

Filed Sept. 24, 1964, Ser. No. 399,016
8 Claims. (Cl. 102—8)

The object of the present invention is an anti-magnetic war-mine, suitable for rapid setting, without any risk, onto any kind of ground, and which can be planted by hand or mechanically by means of vehicles or aircraft, as well as by means of throwing apparatus.

The war-mine, according to this invention, is characterized by a basin made of moulded material, containing the explosive charge, and by a cap made of elastic material, which surmounts said basin and forms, together with a separating flange, an air chamber communicating through a calibrated hole with a bag destined to be inflated whenever a pressure is exerted onto said cap, and to act onto a releasing device, which sets free a striker, while the air compressed by the pressure moreover acts onto a membrane which, in its turn, acts directly on the striker in order to cause it to strike a capsule, the releasing device being arranged in such a way as not to set free said striker as a result of a shock.

In a particular form of execution, the mine is provided with a supplementary safety device which is to be set out of action prior to setting or throwing said mine.

The annexed drawing shows merely by way of example, such a mine, but it goes without saying that the mine without said supplementary safety device is included in the present patent.

FIG. 1 shows a vertical sectional view according to line J—J in FIG. 2.

FIG. 2 shows a view of the mine as seen from above, the mine being deprived of its upper elements. The mine as shown comprises an envelope, the lower part of which being constituted by a basin A made of plastic material, containing an explosive charge S. Said basin shows, in its central part, a hole a_1 closed with a screwed plug P. A fitting Q made of rubber or analogous matter secures tightness.

The charge S shaped as a flat cake, the central hole s_1 of which is occupied by a cylindrical detonator (primer) T presenting a central hole t_1 and containing the capsule U of a unified type, has a lateral groove s_2 . The charge with the detonator and the capsule is held in position by a lid C engaged in the basin A and retained by a ring B which has, in its lower section, a threaded part b_1 being engaged in the thread a_2 of the basin. In its upper section, the ring is provided with a number of notches b_2 which serve to screw the lid by means of a key-wrench.

The lid C has in its center a reinforced part K extending from each side of the lid. The lower part c_1 has the shape of a truncated cone and penetrates into an identically shaped basis t_2 provided in the upper face of detonator T. The central reinforcement is traversed by a square-shaped hole c_2 . Moreover, said lid shows an eccentric hole c_8 extended by a jacket c_9 .

Jacket c_9 is located in the cavity s_2 of the explosive charge S. On the superior face of lid C arise two pivots

2

c_4 , symmetrically arranged with regard to the diameter passing through the axis of hole c_8 and diametrically opposed to this hole, as well as four circular-shaped segments c_6 and two stops c_5 , the latter being placed on either side of hole c_8 . The upper part c_3 of the central reinforcement of the lid has two diametrically opposed trenches (FIG. 2).

On the pivots c_4 are mounted two symmetrical arms n_1 belonging to the releasing device N of the mine. Both these arms n_1 are shaped like a double crank lever whose branches n_5 , opposed to the point of pivoting n_2 , are attracted towards each other by a spring O hooked in two holes n_3 of the arms n_1 . Facing said spring, the lid has a slot c_7 in which spring O can move unhindered. On their inner sides the branches n_5 are thicker than the remaining parts of the arms n_1 thus forming clamping jaws, which will be the object of further description.

The envelope is completed by a cap E, made of elastic material and having the shape of a truncated cone. The rim of said envelope has a U-shaped interior channel, wherein is engaged the rim of a separator flange D made of plastic material.

Cap and flange together are fixed onto the basin by means of ring B fixing lid C. Tightness is secured by a fitting R and by the rim e_1 of cup E.

Separator D presents in its center a hole d_1 , closed by a membrane F which is held in place by a ring H provided with a T-shaped transversal section. Membrane F, made of elastic material, has a peripheral channel wherein is engaged the edge of hole d_1 of flange D. The part h_2 of ring H, forming the jamb of the T, is slightly conical. Separator D furthermore has an eccentric hole d_2 corresponding to hole c_8 of the lid: the rim of said hole d_2 is engaged in a peripheral channel g_1 provided by the orifice of bag G which penetrates into jacket d_9 of the lid, after having transversed the space separating the clamping jaws n_5 from the releasing device N. Bag G is thus flattened in its median part. The orifice of bag G is closed by a stopper I which also serves for maintaining in place said bag and has a calibrated hole of small diameter i_2 .

Located below membrane F is striker L composed of a disk w_2 pressing closely against the membrane, of a shaft of quadrangular section, to be inserted in the corresponding hole of lid C, and of a steel firing-pin M located in an axial hole of shaft w_1 and situated above capsule U.

Said firing-pin is normally hindered to strike the capsule by two pointers n_4 sustained by arms n_1 and penetrating through the trenches of c_3 into the quadrangular hole c_2 , the base of shaft w_1 rests on these pointers located on its trajectory.

Each, basin A, lid C and separator flange D, show an eccentric hole a_3 , c_{10} and d_5 . All these three holes are aligned among each other. Separator flange D shows on its lower side a ring-shaped, threaded protuberance d_6 concentric to hole d_5 , wherein is screwed the upper extremity v_1 of a sleeve V, made of plastic material, the other extremity of which has a bottom part provided with a central hole and with circumferential holes v_2 . This sleeve penetrates through holes c_{10} and a_3 . A threaded ring W and a fitting Y made of rubber or plastic material provide tightness between the sleeve and the basin. An analogous fitting Y is located in the ring-shaped protuberance d_6 .

Within sleeve V is mounted a plunger X of plastic material, supported by a shaft x_2 slightly protruding from the axial hole of the bottom of said sleeve, and showing near its free extremity a diametral hole x_3 , the role of which will be explained below. The plunger bears a hemispherically-shaped head x_1 which constitutes a valve obturating hole d_5 under the action of a spiral spring Z surrounding shaft x_2 . Plunger X is not tightly mounted in the sleeve.

Functioning of said mine is as follows: If a pressure superior to the pressure of calibration is applied on cap E, the air contained between the cap and separator D is compressed, spring Z being sufficiently strong as to resist to this pressure, the air passes through hole i_2 of the stopper I and inflates bag G, which pushes aside the clamping jaws n_5 and, consequently, the pointers n_4 . As soon as both arms are sufficiently displaced in their angular motion around their pivots c_4 , the pointers release the shaft of striker L which, driven by the pressure exercised on it through membrane F by the air compressed in cap E, violently strikes capsule U with its firing-pin M, thus provoking the ignition of detonator T and the explosion of the mine.

The fundamental advantage of said mine lies in its being shockproof, i.e. it cannot be triggered by a shock, since bag G obtains the air which is to inflate it through a little hole, thus preventing an immediate inflating of said bag. In other words, in order to reach an inflation of bag G, the pressure must be applied onto the cap during a certain time: This renders the mine insensitive to shocks and to pressure waves. This insensitivity allows the mechanical planting of these mines without incurring any risk. The releasing device itself is conceived in such a way as not to set free the striker as a consequence of a shock or through dropping of the mine onto the ground. In fact, the two pointers cannot simultaneously move away from the shaft of the striker as a result of a shock, for the arms a_1 , both being mobile on a same plane cannot move through inertia in the same direction. Only one of these arms can move, whilst the other is held back by the central reinforcement c_3 , its pointer n_4 thus retaining the striker.

The safety device incorporated in said mine improves the safety conditions during manipulations prior to setting or throwing the mine. The safety device is operated as follows: after partially extracting shaft x_2 , a pin is inserted into hole x_3 . This pin comes to rest on the bottom of the basin as soon as the shaft is released, which keeps head x_1 at a distance from hole d_5 . Thus the mine cannot explode, for even if a pressure is exerted onto cap E, the releasing device does not work; in fact, instead of penetrating into bag G, the air compressed by the cap escapes unhindered through the holes v_2 after passing through sleeve V. Bag G is therefore not inflated and the pointer n_4 continue to hold back the striker. On removing the pin, spring Z can work again and push head x_1 of plunger X against hole d_5 , closing the latter.

The safety device, as described, may allow of a compensation of the pressure which is present in the chamber delimited by cap E and the separator D. It suffices, for this purpose, that head x_1 does not fully obturate hole d_5 or, in other words, to provide the closing of the hole with very small loss. When, under the circumstances, an increase in temperature causes an expansion of the air in said chamber, this air may gradually escape from the chamber through the imperfectly closed hole d_5 . A decrease in temperature of the air in the chamber will inversely provoke an aspiration of air from outside, again through the valve that is not perfectly sealed. Hence, a heavy rise in temperature will not cause the mine to explode, nor will a sharp fall in temperature render it inactive.

In its simplified form of execution, which does not comprise a supplementary safety device, the mine is identical

with that described with regard to the drawing, except that it is not provided with sleeve and plunger, and that the separator, the lid and the basin are deprived of the eccentric holes d_5 , c_{10} and a_3 .

5 The functioning of said mine is entirely the same as that of the aforementioned mine with safety device put out of action, i.e. with an obturated hole d_5 .

Virtually without any metallic parts, the mine according to the present invention is difficult to trace by means of the detecting devices existing to date.

10 I claim:

1. In a non-magnetic war mine, a basin made of non-magnetic molded plastic material, an explosive charge contained in said basin, a resilient non-magnetic cap mounted over said basin and having a marginal separating flange engaging said basin, said cap and basin forming together an air chamber, a resilient flexible inflatable bag communicating through a calibrated hole with said air chamber, said bag being so arranged as to be inflated when pressure is applied to said cap, a locked striker, a releasing device adapted to release said striker, said releasing device being adapted and mounted to be released by said bag when it is inflated, and a resilient membrane mounted for displacement by the application of pressure on said cap, said membrane being mounted when displaced to displace said striker and to strike said explosive charge, said releasing device being irresponsive to a sudden applied shock.

2. In a non-magnetic war mine, a basin made of non-magnetic molded plastic material, an explosive charge contained in said basin, a resilient non-magnetic cap mounted over said basin and having a marginal separating flange engaging said basin, said cap and basin forming together an air chamber, a resilient flexible inflatable bag communicating through a calibrated hole with said air chamber, said bag being so arranged as to be inflated when pressure is applied to said cap, a locked striker, a releasing device adapted to release said striker, said releasing device being adapted and mounted to be released by said bag when it is inflated, and a resilient membrane mounted for displacement by the application of pressure on said cap, said membrane being mounted when displaced to displace said striker and to strike said explosive charge, said releasing device being irresponsive to a sudden applied shock, said releasing device comprising two symmetrically mounted arms, a lid mounted above said explosive charge, said two arms pivoting respectively on one of their ends on said lid, said arms by their four ends and said lid embracing said inflatable bag, a pointer formed on each of said arms which upon closing together of said arms intercepts said striker, and which releases said striker when the bag is being inflated and separates said arms apart.

3. A mine according to claim 2, said two arms being mounted for displacement angularly in one common plane, a stop, a spring normally holding said pointers against said stop, said arms and their said pointers being mounted to release said striker by moving away from said stop, whereby that under the application of shock, one at most of said arms will by inertia be freed from said striker.

4. A mine according to claim 3, said basin having a threaded rim, a single ring screwed on to said threaded rim, said lid, said separating flange and said cap being fixed on to said basin by said ring.

5. A mine according to claim 4, said separating flange being a disk, having a marginal rim, said cap having a peripheral channel, said rim of said disk being engaged in said peripheral channel of said cap, said cap and said disk being pressed against each other by said ring.

6. A mine according to claim 3, and a supplementary safety device comprising a valve mounted and connected on said air chamber which can be blocked in open position to bring said air chamber into direct communication with the outer atmosphere.

7. A mine according to claim 6, said separator flange having a hole, a spring acting on said valve, and said valve being arranged to close said hole in said separator flange under the action of said spring, a pin mounted for holding said valve open, a shaft mounted on said flange, said shaft being accessible from outside said flange, and being displaceable under the action of said spring, said shaft being provided with a diametral bore adapted to receive said pin.

8. A mine according to claim 7, said valve being so arranged that said valve does not seal hermetically tight said hole in said separator flange, so that air may escape from or enter said chamber, as a result respectively of dilations or contractions of said chamber due to variations of temperature.
